J. MATTSON

GRAIN DOOR

Filed Feb. 17. 1923

Attorney

UNITED STATES PATENT OFFICE.

JACOB MATTSON, OF DULUTH, MINNESOTA.

GRAIN DOOR.

Application filed February 17, 1923. Serial No. 619,546.

To all whom it may concern:

Be it known that I, JACOB MATTSON, a citizen of the United States, residing at Duluth, in the county of St. Louis and State 5 of Minnesota, have invented certain new and useful Improvements in Grain Doors, of which the following is a specification, reference being had therein to the accompanying drawing.

10 This invention relates to car doors and has special reference to improvements in what is commonly known as grain doors.

The principal object of the invention is to provide a better and more efficient door than 15 those heretofore known.

Other objects and advantages will appear in the further description of the invention.

Referring to the accompanying drawing forming part of this application and in 20 which like reference characters indicate like parts:

Figure 1 is an outside elevation of a fragmental portion of a box car, showing one of my improved doors as applied to the opening 25 therein;

Figure 2 is a transverse sectional view showing parts of the door structure in elevation and other parts in section for convenience in illustration;

30 Figure 3 is an edge elevation of one of the line sheaves in the door post; and

Figure 4 is a fragmental illustration of the upper end of the reinforcing bar.

1 represents the door opening in the car 35 which is surrounded by the floor 2, side posts 3-3, and lintel 4.

My improved door is preferably made of sheet metal and is illustrated at 5, the same being normally free from direct attachment

40 to the surrounding walls of the door, though across the lower edge of the opening of the door and below the surface of the floor is installed a metal strip indicated at 6, forming a slight depression or groove in which 45 the lower edge of the door 5 rests when in position as a closure. This is to insure no grain getting by under the lower edge of the door, as well as forming a desirable support for the entire lower edge of the door.

50 The door 5 is provided upon its outer face and adjacent the side edges thereof with guiding and upstanding angle-bars 7 which are permanently attached thereto. Part way down from the upper end of these angle-bars

55 a piece 8 of the outwardly extending web

of each angle-bar is cut and bent inwardly, and also provided with a hole into which lift ropes 9 are attached. These ropes each lead upwardly over a sheave 10 let into the inner face of the door post 3 and covered with a strap 11, from thence the ropes lead downwardly through gas pipe guides 12 through the floor of the car where one is wound around the winding drum 13 on the shaft 14 journaled beneath the car, and the other 60 goes around the sheave 15, then longitudinally of the car under the door to the drum 13 and is wound with the other line; both being raised and lowered simultaneously. The shaft 14 is operated manually by a suitable crank 16 and said shaft is optionally held against backward rotation by a suitable pawl and ratchet wheel indicated at 17; these elements for raising and lowering a car door being old in the art.

As is evident by this means the door may be raised or lowered into position as desired and the clips 8 and sheaves 10 are so positioned that the door may be conveniently raised approximately one-half its height 80 where a Z-bar iron 18 is provided for a track for the door, said bar being rigidly fixed to the inner upper edge of the lintel 4. For engagement with this bar the door 5 is provided near each upper corner with an upstanding flat metal hook member 19 which may be readily caused to overlap the Z-bar track by manual manipulation of the door when it is raised to proper position for such purpose, and the door thus suspended 85 on this track and slid longitudinally of the door opening out of the way where it may be either housed or fastened in any desired manner.

As an additional provision for removal of the door I form in the upward projecting portion of the Z-bar slots 20 directly above the hooks 19 so that if preferred, and which may be desirable at the initial opening of the door before the load of the car is fully 90 removed, the hooks 19 may be caused to engage the slots 20 and the door swung directly up to the ceiling of the car where it may be held with a suitable hook or other means not shown, as this bodily swinging upwardly of a car door is common.

I further propose to form a third slot, the same as those illustrated at 20, but spaced the proper distance to move the door laterally one width thereof, as it may be de- 110

sired to slide the door into that position which is indicated in dotted lines at 22 before swinging it up to the ceiling, this positioning of the door being particularly desirable when more head room is required adjacent the major portion of the doorway.

As a reinforcing member or strong back for the door, I employ a T-beam or iron indicated at 23, slightly greater in height than the door opening. The web of this T-iron is cut away at an angle adjacent both ends and some distance therefrom forming overlapping ends 24 and 25 and into the lower innermost edge of the lintel 4 is formed a notch 26 for the reception of the overlapping end 24 where it is retained by any form of suitable gravity keeper 27 pivotally suspended at 28 in the inner face of the lintel; while in the floor of the car adjacent the edge of the groove 6 is a recess for the overlapping end 25 of the strong back.

It is quite evident that this reinforcing

member may or may not be resorted to as circumstances may require.

Having thus described my invention, what I claim and desire to secure by Letters Patent, is:

The combination with a track presenting an upwardly directed flange extending transversely of a door opening, said flange having transversely spaced holes therethrough, of a door having upwardly extending hooks for overlapping engagement with said flange for sliding movement of said door, said hooks being spaced to register with the holes in the flange to permit the hooks to engage in said holes for pivotal movement of said door, substantially as described.

In testimony whereof I hereunto affix my signature in the presence of two witnesses.

JACOB MATTSON.
